UNITED STATES PATENT OFFICE.

WILLIAM J. NEWMAN, OF CHICAGO, ILLINOIS.

LIGHT FOR WELLS OR CAISSENS.

1,134,959.

Specification of Letters Patent.

Patented Apr. 6, 1915.

Application filed August 28, 1913. Serial No. 787,115

To all whom it may concern:

Be it known that I, WILLIAM J. NEWMAN, a citizen of the United States, residing at Chicago, in the county of Cook and State of Illinois, have invented certain new and useful Improvements in Lights for Wells or Caissons, of which the following is a specification.

In digging deep wells, such for instance as are frequently dug for building foundations, it is desirable to have a strong and effective light so that the workmen can see to work satisfactorily. Heretofore, it has been more or less customary to use drop lights from city service wires, but such lights necessitate wires running down into the wells, which are more or less troublesome, and which are also more or less liable to short circuits, as well as requiring frequent adjustments and the attention of an electrician. In order to overcome such objections and to provide a simple and efficient method of lighting wells or caissons, I have devised the light forming the subject of this invention. In accordance with this invention I provide a novel and improved form of light which is portable, which may be hung at any desired position in the well, which may be readily renewed or replaced, and which has such other advantages as will appear from the following description.

In the accompanying drawings illustrating a preferred form of my invention; Figure 1 is a sectional view of a portion of a well showing my improved light hung therein; Fig. 2 is an enlarged longitudinal sectional view of the light; and, Fig. 3 is a cross-sectional view of the same.

In my improved light, I utilize a battery, such as the battery 4 as shown in the drawings, for the source of electricity. This battery is preferably of the storage type but any suitable form may be used. The battery 4 is inclosed in the box or casing 5, having a cover 6, which is hinged at 7 and provided with a suitable lock or catch 8. The bottom 9 of the box is inserted at some distance above the lower edges of the sides thereof, in order to form a downwardly opened chamber or recess 10. This chamber or recess is preferably coated or lined on the inner side with suitable reflecting material 11. One or more lamp sockets 12 are secured to the lower side of the bottom 9 for receiving the lamps 13, which lamps do not

extend as low as the downwardly projecting sides of the chamber 10.

In order to make a safe and convenient connection from the battery to the lamps, I provide a tube 14 secured within the box 5, through which the wires 15 and 16 are passed. These wires connect between the battery terminals and the lamp sockets. By means of this arrangement it will be readily seen that the upper ends of the wires may be readily disconnected for inserting a new battery without changing the other connections.

When storage batteries are used, it is desirable or necessary that they hang in a vertical position. In order to insure the box 5 hanging in such position I provide a bail 17, which is pivoted at 18 to the sides of the box, and which is provided with a hook 19 for engagement with the hoops or braces 20 of the well. By means of this connection it will be seen that the hook may engage with the hoop at the edge of the well, and yet the box 5 will remain in vertical position. When in such position the light will be reflected downwardly toward the bottom of the well, the lamps being in the most effective location for this purpose, and the reflecting material lining the lower chamber 25 further tends to throw the light downwardly where it is most needed. When the device is not hanging on the hook, it may rest upon the floor or other suitable place, as the sides of the box will protect the 30 lamps 13.

Having thus described my invention, which however I do not wish to limit to the exact construction and arrangement herein shown and described, except as specified in the appended claims, what I claim and desire to secure by Letters Patent is:

1. In a light for wells, the combination of a rectangular casing, a partition in said casing, dividing the same into upper and lower compartments, a cover for the upper compartment, a battery mounted in said upper compartment, one or more lamp sockets secured to the lower side of the partition, connections from said battery to said sockets, lamps for said sockets, said partition being arranged sufficiently above the lower edge of the casing so that the lamps do not extend to the lower edge, and a bail pivotally secured to the sides of said casing, substantially as described.

2. In a device of the character set forth,

the combination of a box having its bottom located above the lower edges of the sides thereof, a cover, a battery mounted in said box, a tube extending from the top of the box to a point below the bottom, electric lamps secured to the lower side of the bottom member, connections from the battery extending through said tube to the lamps, and means for supporting said box.

10 3. In a device of the character set forth, the combination of a box having its bottom member located at some distance above the lower edges of the side members to form a

lamp recess, a reflector arranged in said recess, a lamp mounted in said recess above the lower edges of the side members, a tube extending from said recess to approximately the top of the box, a battery in said box, electrical connections from the battery through said tube to the lamp, a hinged cover for said box, a bail pivoted to the sides of the box, and a hook secured to said bail.

WILLIAM J. NEWMAN.
